UNITED STATES PATENT OFFICE.

CLEMENT V. HILL, OF TRENTON, NEW JERSEY.

FASTENER FOR DOORS.

1,123,741.

Specification of Letters Patent.

Patented Jan. 5, 1915.

Application filed September 25, 1914. Serial No. 863,518.

To all whom it may concern:

Be it known that I, CLEMENT V. HILL, a citizen of the United States of America, residing at Trenton, in the county of Mercer and State of New Jersey, have invented certain new and useful Improvements in Fasteners for Doors, of which the following is a specification.

For the purpose of illustrating my invention I have shown it mounted on a refrigerator door.

The object of my invention is to provide a fastening mechanism which will hold the door tightly on its jamb with an air tight joint, said mechanism being so constructed that it may be as readily operated from the inside of the door as from the outside thereof, the latch bolt being of a type that will automatically engage its keeper as soon as the door is closed, there being tension means to hold the bolt firmly in its locked position, but the mechanism for operating the bolt is such that the tension of the said means is overcome, with a minimum pull in the act of opening the door; and with these and other objects in view my invention consists of the parts and combination of parts, as will be more fully hereinafter set forth.

In the drawings: Figure 1 is a front elevation of a portion of a door and its jamb with my improved fastener applied thereto. Fig. 2 is a vertical sectional view on the line 2—2 Fig. 1, showing the fastening mechanism in latched position. Fig. 3 is a similar view showing the parts with the bolt elevated to unlatched position as just in the act of leaving its keeper. Fig. 4 is a vertical sectional view through a door showing the fastening mechanism in elevation and partly in section. Fig. 5 is a detail view showing the ratchet tension for the spring. Fig. 6 is a top plan view of Fig. 1, parts being in section.

The reference numeral 1 designates a jamb, and 2 a door of suitable construction, while 3 represents a packing carrier by the door or by the jamb. The packing is shown because I have elected to describe my inven-

tion in connection with a refrigerator, but, of course, it will be understood that my improved latch is not limited, in its application, to refrigerators.

The keeper 4 is secured to the jamb by means of the screws or bolts 5, and is provided with a nose 6 having a cam face 7 and 50 a cam face 8, the latter cam face, when the keeper is assembled on a door jamb, being spaced from the jamb to form a recess 9 for the reception and retention of the latching bolt.

A plate 11 is secured to the door by any suitable means, such as screws, and is substantially of L-shape to provide a base upon which the working parts of the latch may be mounted thereby eliminating the liability of 65 the parts being lost in transit and reducing to a minimum the number of screws or bolts necessary to secure the parts to a door.

Arms 12 and 13 are formed integral with the base plate 11 and project forwardly 70 therefrom when the plate is secured to a door. A revoluble shaft 14 is journaled in said arms 12 and 13 and is provided with a crank arm 15 on the end of which is mounted an antifriction roller 16 which is adapted 75 to enter the recess 9 in the keeper and thereby securely latch the door in its closed position, as shown in the drawing. A coiled spring 17 is secured around the shaft 14, one end thereof being anchored at 18 to the arm 80 12 while the other end is anchored to a tension ratchet wheel 19 which in turn is revolvably mounted on the shaft 14 and is held in adjusted position by means of a key 20 mounted on the arm 13.

Inasmuch as the pin 20 keys the ratchet to the arm 21, the ratchet revolves on the shaft 14, when the arm is moved, but it does not move relatively to the arm.

An arm 21 is keyed to the shaft 14 by 90 means of which the shaft is revolved and the latch bolt withdrawn from the keeper when the parts are operated in the act of opening and closing the door. This arm is provided with a reduced end 22 to which is 95 pivotally secured a link 23, the forked end

24 thereof being adapted to receive said reduced end 22.

The door is provided with a transverse opening 25 in which the rod or stem 26 is positioned, the opening being, relatively, of greater diameter than the rod or stem shown, the inner end of the rod or stem being provided with a knob 27. The inner end of the opening is closed by means of a 10 cup plate 28 having an opening through which the rod passes, said plate being packed with a packing 29, preferably felt, which will prevent the ingress and egress of air around through the opening 25, which, 15 in the case of refrigerators, is very essential.

The forward or outer end of the rod is provided with an integral operating handle 30 and with a striking plate or lug 31 which is of such size that it will close and seal the 20 outer end of the opening 25, when the door is closed, thus providing another seal against the ingress or egress of air. Intermediate the striking plate 31 and handle 30 the rod 25 is enlarged as at 32 through 25 which is formed a slot 33 in which is pivotally secured the reduced upper end 34 of the link 23, and the reduced lower end 35 of the upper link 36, the upper end of the link 36 being forked, as at 37, and pivoted 30 to the lug 38 which is integral with the base plate 11.

When the door is closed the parts are in the position shown in Fig. 2. Now assuming that it is desired to open the door the 35 parts are operated, from the outside, by grasping handle 30 and pulling it in the natural direction to swing the door open, when the parts will assume the position shown in Fig. 3 and by continued pull the 40 door will swing to full open position. When the handle 30 is pulled outward the outer end portion of the rod 26 is elevated, as shown in dotted lines in Fig. 3, by reason of the fact that the upper end of the link 36 is 45 anchored to the base plate 11 and swings in an arc from that point, and this upward movement results in pulling the link 23 bodily upward thereby, elevating the inner end of the arm 21 and thus revolving the shaft 50 14 against the tension of the spring 17, thus swinging the arm 15 and elevating the roller 16 above the nose 6 whereupon the door is free to be swung open.

In closing the door the roller 16 rides up 55 the cam face 7 and drops into the recess 9 and by the coöperation of the spring 17 and the cam face 8 the door is pulled against the jamb and forms therewith a tight joint.

In the use of refrigerators it is customary 60 to close the door tightly so that it is necessary to provide some means for operating the latch from within the refrigerator therefore I extend the rod or stem 26 within the refrigerator and provide it with a knob 27

so that the lock may be operated by pushing 65 the rod outward. I prefer to use a knob on the inner end of the rod as it presents an enlarged surface against which the body may be conveniently pressed, in case the operator requires both hands to carry goods 70 from the refrigerator.

It will be observed that in operating this fastener no unusual or unnatural movements are necessary; the natural movement of the arm in opening and closing the door being 75 all that is necessary to operate the fastener.

By reason of the link movement herein described which gives a very powerful leverage, I am enabled to put the spring 17 under very heavy tension which results in 80 a stronger pull of the latching roller 16 on the cam face 8 which in turn results in a tighter joint between the door and jamb.

What I claim is:

1. In a fastener for doors, the combination 85 with a latch for holding the door closed and mounted upon a horizontally disposed axis parallel with the vertical plane of the door, an operating rod, extending through the door and having a limited vertical movement at its outer end, but fixed against vertical movement at inner end, and a vertically disposed operating device connected to the latch and the rod.

2. In a fastener for doors, the combination 95 with a latch for holding the door closed and mounted to rotate upon an axis parallel to the vertical plane of the door, an operating rod constructed to pass through an opening in a door and extend beyond the 100 front and rear face of the door, and a pivoted connection between the outer end of said rod and the door and a swinging connection between the outer end of the rod and the said latch.

3. In a fastener for doors, the combination 105 with a latch for holding the door closed and mounted to rotate upon an axis parallel with the vertical plane of the door, and an operating rod, a swinging connection between the said rod and door and a link connection between the said rod and said latch.

4. In a fastener for doors, the combination 115 with a latch for holding the door closed and mounted upon an axis parallel to the vertical plane of the door, of an operating rod extending through a transverse opening in the door, said opening being of greater diameter than the rod, a handle on each end of the rod, a link pivotally connected to the 120 door and to the outer end of the rod, a link pivotally connected to the said rod and to said latch, whereby a movement of the rod in the direction of its axis will rotate said latch upon its axis.

5. In a fastener for doors, the combination 125 with a base plate, arms extending outwardly from said plate, a shaft revolvably

journaled in said arms parallel with the vertical plane of the plate, a latch crank at one end extending in the direction of the plate and an operating crank arm at the other end 5 of the shaft also extending in the direction of said plate, and a tension spring connected with said shaft, of an operating rod, a link pivotally connected to said rod and to the

operating crank arm, and a link pivotally connected to said rod and said base plate.

In testimony whereof I affix my signature in presence of two witnesses.

CLEMENT V. HILL.
